UNITED STATES PATENT OFFICE.

BERTHA P. TURGEON, OF NEW YORK, N. Y.

STRAW-HAT PROTECTOR.

Application filed March 7, 1929. Serial No. 345,208.

This invention relates to protectors for straw hats and the general object of the invention is to provide a very convenient protector of this character made of waterproof material and so formed that it may be readily applied to a hat to cover the crown and upper and lower surfaces of the brim thereof.

A further object of the invention is to provide a protector of this character having what 10 might be termed a half pocket receiving the forward edge of the brim, the remainder of the brim being protected by flaps forming continuations of the lower wall of this pocket having connection with the pocket wall and 15 with one another permitting an expansion of the opening defined by the inner margins so that this portion of the protector may be expanded to permit the insertion or removal of the hat from the protector.

20 My invention is illustrated in the accompanying drawings, wherein:—

Figure 1 is a perspective view of the hat protector embodying the present invention;

25 Figure 2 is a bottom plan view of the same; Figure 3 is a sectional view taken transversely of the rim covering the portion of the protector and a portion of the side and top.

30 Referring to the drawings, it will be seen that the protector, which is made of the same material as slickers, though it may be made of any suitable material as for instance of fine oiled silk or the like, is so formed as to provide a top 10 adapted to cover the top of 35 the hat crown, side 11 which goes around the crown and which is formed with a seam in the back and the top section 12 which is annular and covers over the top of the hat brim. These three sections are connected to each 40 other along the seams 13 by water-proof cement, rubber cement or the like so that all the seams are water-proof, and thus the three pieces 10, 11 and 12 are practically one complete piece.

45 The lower face of the brim is protected by an oval flap which may be roughly divided into three sections 14, 15 and 16. These sections are each secured about their outer edges as indicated at 17 to the outer marginal edge 50 of the part 12 by water-proof cement or the like. This flap has at points transversely alined with one another folds 18 and has at one end which is adapted to be disposed over the rear portion of the brim of the hat a third fold 19. The outer flap of each of the folds

18 and 19 is secured by snap fasteners 20 or the like and it will be obvious that by releasing these snap fasteners and spreading the flap at these folds, the size of the inner opening 21 defined by this flap will be increased 60 to a point where the hat brim may be readily inserted into the pocket formed between the brim 12 and the section 14 which has no fold formed therein.

The sections 14, 15 and 16 are preferably 65 formed as separate pieces of material for facilitating any preparation of the flap, these pieces being secured to one another with water-proof cement. A seam 22 between the pieces may conveniently occur at 70 such point as to provide a double thickness of material, reinforcing the snap fasteners at the outer flap of the fold and each section is preferably reinforced at points underlying the coacting elements of the snap fasteners as indicated at 23. The section 14 which is intended for disposition at the forward portion of the hat brim and which is subjected to the greatest strain when applying and removing the cover is preferably 75 80 formed from a double thickness of material or otherwise reinforced to enable it to withstand such usage.

In applying a device of this character to the hat, the protector is first placed over the 85 crown of the hat, and one side of the oval flap pulled over the brim at one side thereof. The front of the protector which includes the section 14 of this flap is then worked over the brim of the hat, after which the sections 15 and 16 are pulled thereover and securing elements at the folds engaged with one another. This operation is reversed in removing the protector from the hat.

A device of this kind can be put on and 90 taken off very easily and it fits on the straw hat tightly and can be made, of course, of different colors. The device can be rolled up and put in a bag made of water-proof material and can be put in any coat pocket. 100 While I preferably use the material such as is used for slickers or fine oiled silk, I do not wish to be limited to this. A device of this kind thoroughly protects the straw hat against rain and may be readily applied, 105 taken off or carried.

I claim:—

1. A hat protector of water-proof material formed to provide a covering for the crown of the hat and the upper face of the brim, a 110

covering for the lower face of the brim in the form of a flap secured at its outer marginal edge to the covering for the upper surface of the brim, said flap having folds at 5 its opposite sides and at one end thereof, the folds at their outer edges being secured and at their inner edges being free to thereby permit expansion of the opening defined by said flap and to permit insertion and removal 10 of the hat to the protector.

2. A hat protector of water-proof material formed to provide a covering for the crown of the hat and the upper face of the brim, a covering for the lower face of the brim in 15 the form of a flap secured at its outer mar-

ginal edge to the covering for the upper surface of the brim, said flap having folds at its opposite sides and at one end thereof, the folds at their outer edges being secured and at their inner edges being free to thereby 20 permit expansion of the opening defined by said flap and to permit insertion and removal of the hat to the protector, said folds having securing elements associated therewith whereby they may be secured in the contracted position of the inner marginal edge portions of the flap. 25

In testimony whereof I hereunto affix my signature.

MRS. BERTHA P. TURGEON.
